(57) **CLAIM**

The ornamental design for a pick, as shown and described.

DESCRIPTION

FIG. 1 is a front, top, perspective view of a pick, according
to an embodiment of a new design;

FIG. 2 is a rear, bottom, perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

Portions of the pick depicted in broken lines in the drawings
form no part of the claimed design.

Any combination of the illustrated features, including
claimed features and non-claimed features, may be claimed
in this application or a continuing application claiming
priority to this application by converting any portion of the
broken lines to solid lines, any portion of the solid lines to
broken lines, or both.

1 Claim, 8 Drawing Sheets
